UNITED STATES PATENT OFFICE

CONSTANCE D. JOHNSON, OF PENDLETON, OREGON

DESIGN FOR A DOLL

Application filed March 26, 1928. Serial No. 26,006. Term of patent 14 years.

To all whom it may concern:

Be it known that I, CONSTANCE D. JOHNSON, a citizen of the United States, residing at Pendleton, in the county of Umatilla, State of Oregon, have invented a new, original, and ornamental Design for a Doll, of which the following is a specification, reference being had to the accompanying drawing, forming part thereof.

Fig. 1 is a front elevation of a doll showing my new design; and Fig. 2 is a side view of the same.

I claim:

The ornamental design for a doll, as shown.

CONSTANCE D. JOHNSON.
